UNITED STATES PATENT OFFICE.

JOSEPH SYLVAN, OF CHICAGO, ILLINOIS, ASSIGNOR OF ONE-HALF TO LOUIS A. RUDA,
OF CHICAGO, ILLINOIS.

VENTILATOR.

1,293,975.

Specification of Letters Patent. Patented Feb. 11, 1919.

Application filed August 29, 1918. Serial No. 251,867.

To all whom it may concern:

Be it known that I, JOSEPH SYLVAN, a citizen of the United States, and a resident of Chicago, in the county of Cook and State 5 of Illinois, have invented certain new and useful Improvements in Ventilators; and I do hereby declare that the following is a full, clear, and exact description thereof, reference being had to the accompanying 10 drawings, and to the letters of reference marked thereon, which form a part of this specification.

This invention relates to improvements in 15 ventilators for roofs, skylights and the like, and consists of the matters hereinafter described and more particularly pointed out in the appended claims.

One of the objects of the invention is to 20 provide a ventilator made up of a comparatively few parts, which are so formed and so arranged with respect to each other, that when a current of air passes through the ventilator, a suction action is produced in the ventilator, which will suck or draw the 25 air out of the room or chamber with which the ventilator is connected, and properly ventilate the same.

Another object of the invention is to so 30 arrange the various parts, that the ventilator will exclude the entrance of wind, rain and snow into the room or chamber being ventilated and will efficiently drain itself of such moisture as will form on its interior surfaces.

35 These objects of the invention, together with the many advantages thereof, will be more apparent as I proceed with my specification.

In the drawings:

40 Figure 1 represents a view in perspective of a ventilator embodying my invention.

Fig. 2 represents a detail view in perspective of a wing plate embodied in the improved ventilator.

45 Fig. 3 represents a vertical, transverse, sectional view through the ventilator in a plane indicated by the line 3—3 of Fig. 1.

Fig. 4 represents another vertical, transverse sectional view through the same, the 50 plane of the section being indicated by the line 4—4 of Fig. 1.

Fig. 5 represents a top plan view of the ventilator.

Fig. 6 represents a horizontal, sectional 55 view through the ventilator, the plane of

the section being indicated by the line 6—6 of Fig. 1.

Referring now in detail to that embodiment of my invention illustrated in the accompanying drawings:—10 indicates as a 60 whole, the improved ventilator which is preferably made entirely of sheet metal. 11 indicates the usual, upright, tubular stem of the ventilator which is provided with a flange 12 at its bottom for the attachment of 65 the ventilator as a whole to the roof or skylight of the room or chamber to be ventilated.

13 indicates the conical cover or top of the 70 ventilator, which is spaced a suitable distance above the top end of the stem and is supported therefrom in a manner soon to appear. As shown, said top is made substantially rectangular in plan, is longer in one direction than it is in the other, and has 75 rounded corners 14. (See Fig. 5.)

15, 15 indicate opposed, upright weather 80 shields which extend across the shorter ends of the top 13 and which are secured to the under side of said top at said ends, in any 85 suitable manner. The bottom ends of said shields extend into a plane below that of the top end of the stem 11 and said bottom ends of said shields are spaced from and connected to said top end of said stem by 90 substantially horizontally disposed plates or walls 16 which are of a width less than the diameter of the stem 11. Said plates or walls are slightly inclined downwardly from the shields 15 toward the stem 11 and 95 act both as barriers against upward air currents at these points, and as drain plates for such moisture as may lodge thereon. The marginal edges 17 of said shields are rounded to follow the curvature of the rounded 95 corners 14 of the top 13 and are of an arcuate length equaling the arcuate length of said rounded corners 14.

20, 20 indicate opposed wing plates (see 100 Figs. 2 and 4) which are arranged in a plane between and preferably at right angles to the plane of the weather shields 15. Said wing plates are fixed at their top ends to the under side of the cover or top 13 in planes spaced from the longer sides of said 105 top, and are fixed at their bottom ends to the top end of the tubular stem 11 by rivets as shown in Figs. 1 and 6, so that said cover or top is held in proper relation to said stem. The construction thus far described, pro- 110

duces a rigid ventilator capable of withstanding high wind pressure without warping or collapsing.

Each wing plate 20 includes a tapering middle web 21 that diverges downwardly and outwardly from top to bottom, and tapering side parts 22, each of which has a lateral, marginal flange 23, that extends vertically from top to bottom of said wing plate. The side parts 22 and the web 21 of each wing plate, blend into each other or come together at the top, in an arc concentric with the stem 11, as shown in Figs. 1 and 5. The bottom ends of the webs 21 and side parts 22 of each wing plate 20, together with the top end of the stem 11, provide mouths 24, (see Figs. 1, 4 and 6) and in said mouths are provided deflector plates 25 which are fixed to the top end of the stem 11 and extend downwardly and outwardly so as to partially restrict said mouths.

Thus such air as will enter one of said mouths on one side of the ventilator, will be directed away from the top of the stem 25 by the said deflector to follow up the interior surfaces of the web 21 and side parts 22 of the associated wing plate (see Fig. 4) to meet and coact with the air current passing horizontally through the ventilator by 30 means of the spaces or passageways 26 (see Fig. 6) defined by the edges of the curved margins 17 of the weather shields and the outer surfaces of the side parts 22 and flanges 23 of the wing plates 20. Said deflectors also act to prevent the entrance of rain and snow through the mouths 24 directly into the stem 11.

Such air currents as pass horizontally through the ventilator will suck out and 40 carry with them, that air which is located in the stem 11 and reduce the pressure therein behind said wing plates and tend to exhaust the air in said stem and produce an upward current of air therethrough, from 45 the room or chamber being ventilated.

By reason of the somewhat tortuous path of the wind or moving air current passing horizontally through the ventilator, no air, rain or snow can back down through the 50 stem and into the room being ventilated.

My improved ventilator consists of but few parts which may be easily made and assembled, and when so assembled will operate efficiently for the intended purpose. The 55 parts are so arranged as to brace one another so that the ventilator readily withstands wind pressure without warping or becoming out of shape.

While in describing my invention, I have 60 referred to certain details of construction and arrangement of parts, I do not wish to be limited thereto, except as may be pointed out in the appended claims.

I claim as my invention:

65 1. A substantially rectangular ventilator

for roofs, skylights and the like, comprising in combination, an upright, tubular stem, a top spaced vertically above said stem, a pair of opposed weather shields fixed at their upper ends to said top and at their lower ends 70 to said stem, and a pair of opposed wing plates arranged at a right angle to said shields and fixed to the sides of said top and converging downwardly toward and outwardly away from said stem, said wing 75 plates being attached at their bottom ends to said stems.

2. A ventilator for roofs, skylights and the like, comprising in combination, an upright, tubular stem, a substantially rectangular top spaced vertically above said stem, a pair of oppositely disposed, vertically arranged weather shields fixed at their upper ends to the ends of said top, plates connecting the lower ends of said shields with and holding them in spaced relation from the top end of said stem, said shields having curved marginal parts, and a pair of opposed wing plates arranged at right angles to said shields and fixed to the sides of said top 90 and converging downwardly toward and outwardly away from said stem, said wing plates being fixed at their bottom ends to said stem and having upright marginal parts engaging with the plates connecting the 95 shields to said stem.

3. A ventilator for roofs, skylights and the like, comprising in combination, an upright tubular stem, a substantially rectangular top longer than it is wide spaced vertically above said stem, a pair of opposed weather shields fixed to the ends of said top and to the stem respectively, and a pair of opposed wing plates arranged in a plane at right angles to said shields and fixed to the 105 sides of said top and converging downwardly toward and outwardly away from said stem, the bottom ends of said wing plates being fixed to the top ends of said stem and defining mouths opening into the ventilator, 110 and deflector plates in the mouths defined by the bottom ends of said wing plates.

4. A ventilator for roofs, skylights and the like, comprising in combination, an upright tubular stem, a top spaced vertically 115 above said stem, a pair of opposed weather shields fixed to said top, plates connecting the bottom of said shields with and holding them in spaced relation outwardly away from said stem, a pair of opposed wing plates 120 fixed to said top and converging downwardly toward and outwardly away from said stem to provide mouths opening into said ventilator, said wing plates including upright marginal flanges which are fixed to the top end of the stem, and deflector plates fixed to the top of said stem and extending into said mouths and partially restricting the same.

5. A ventilator for roofs, skylights and 125

the like, comprising in combination, an upright, tubular stem, a substantially rectangular top, longer than it is wide, spaced vertically above said stem, said top having 5 rounded corners, two opposed, vertically arranged weather shields fixed to said top at its ends, said shields having marginal edges curved to conform with the rounded corners of said top, plates connecting said 10 shields with and holding them in spaced relation outwardly away from said stem, two opposed wing plates fixed to said top near its sides, said wing plates being arranged at right angles to said shields and converging

downwardly toward and outwardly away 15 from said stem to provide mouths, and deflector plates fixed to said stem and extending outwardly into said mouths and partially restricting the same.

In testimony that I claim the foregoing 20 as my invention, I affix my signature in the presence of two witnesses, this 24th day of August, A. D. 1918.

JOSEPH SYLVAN.
